(57) **CLAIM**

The ornamental design for a SWITCH COVER as shown and described.

DESCRIPTION

FIG. 1 is a front view of the new design;

FIG. 2 is a left-side view thereof;

FIG. 3 is a right-side view thereof;

FIG. 4 is a top view thereof;

FIG. 5 is a bottom view thereof;

FIG. 6 is a rear view thereof;

FIG. 7 is a top, right-side, and front perspective view thereof; and

FIG. 8 is a bottom, right-side, and front perspective view thereof.

The broken line showing of portions of the SWITCH COVER is for the purpose of illustrating portions of the article and forms no part of the claimed design.
